UNITED STATES PATENT OFFICE

99,608

DESIGN FOR A FOOD CONTAINER UNIT

Lewis H. Scurlock, Chicago, Ill.

Application February 27, 1936, Serial No. 61,382

Term of patent 14 years

To all whom it may concern:

Be it known that I, Lewis H. Scurlock, a citizen of the United States and resident of Chicago, in the county of Cook and State of Illinois, have invented a new, original, and ornamental Design for a Food Container Unit, of which the following is a specification, reference being had to the accompanying drawing forming a part thereof:

Fig. 1 is a plan view of a food container unit showing my new design.

Fig. 2 is a side elevation of said unit.

The device of my design comprises the several container elements shown in solid black lines in the drawing, combined with a base structure shown in dotted lines. The dominant features of the design are shown in the solid black lines.

I claim:

The ornamental design for a food container unit, as shown and described.

LEWIS H. SCURLOCK.
